UNITED STATES PATENT OFFICE.

WILLIAM T. DAVIS, OF BATTLE CREEK, MICHIGAN.

THREE-BARRELED GUN.

SPECIFICATION forming part of Letters Patent No. 278,688, dated June 5, 1883.

Application filed April 26, 1882. (No model.)

To all whom it may concern:

Be it known that I, WILLIAM T. DAVIS, of Battle Creek, in the county of Calhoun and State of Michigan, have invented certain new and useful Improvements in Guns; and I do hereby declare the following to be a full, clear, and exact description of the invention, such as will enable others skilled in the art to which it pertains to make and use the same.

10 My invention relates to an improvement in fire-arms, and more particularly to that class thereof designed for sporting purposes, the object of the invention being to attach a rifle-barrel to the top and between the barrels of a 15 double-barreled breech-loading shotgun, and to provide lock mechanism for firing the rifle-barrel, which shall be arranged to be operated by the firing mechanism of either of the shot-barrels, and yet to be so far independent of 20 such mechanisms that they will not be disturbed in the performance of their peculiar functions.

With these ends in view my invention consists in certain details of construction and combinations of parts, as will be hereinafter described, and pointed out in the claims.

In the accompanying drawings, Figure 1 is a view in side elevation of a combined shotgun and rifle constructed in accordance with my invention. Fig. 2 is a vertical longitudinal section, showing the lock mechanism of the rifle-barrel and its connection with the firing mechanism of one of the shot-barrels, and Fig. 3 is a view in transverse section of the shot and rifle barrels.

The rifle A is attached to the top of and between the two shot-barrels B in any desired manner, the said barrels being secured to the breech-block C by any approved means. The 40 lock-frame D, inclosing the devices for firing the rifle-barrel, is secured to the rearwardly-extending arm E of the breech-block by a screw, F, and by a lug, G, made integral with or attached to the lower face of the outer end of the lock-frame, and adapted to be received within a recess, H, formed in the breech-block, the particular function of the said lug being to enable the lock-frame to withstand the recoil resulting from the discharge of a cartridge 45 in the rifle-barrel.

A firing-pin, I, adjusted to have longitudinal reciprocation in the forward end of the lock-

frame, is actuated by the plunger J, which is encircled by the spiral spring K. The upper face of the said firing-pin is cut away, to receive the end of a screw, L, which limits the reciprocatory movement of the pin and prevents it from being displaced. If desired, however, the firing-pin may be attached directly to the outer end of the plunger, although the construction shown is preferred. The rear end of the plunger is journaled in a ring-shaped bearing, M, which is transversely slotted and held in position by a pin, N, the lower end of the said bearing being cut away, to permit the dog F' to engage with the notch O, formed in the lower side of the plunger, when the same is retracted, as shown in the drawings, by the cocking-arm P, the lower end of which is pivoted to the extreme rear end of the lock-frame D. The rear end of the plunger, as well as the lug Q, formed on the inner face of the cocking-arm, is vertically slotted to receive the connecting-link R. A spring, S, arranged to impinge against the dog, is designed to maintain it in a normal condition of readiness to engage with the slot O, formed in the plunger, as described.

In firing the rifle-barrel the engagement between the plunger and dog is broken by the pin T, which reciprocates in a vertical hole formed in the gun-stock, the upper end of the said pin being arranged to impinge against the lower face of the dog F', while its lower end is supported upon the edge of one of the plates U, 85 formed integral with or attached to the triggers V. When the plate upon which the pin rests is moved by retracting the trigger, the pin will be elevated and impart its motion to the dog, which will be rocked on its pivot and released from its engagement with the plunger, which will at once be projected against the firing-pin by the force of the spring K, and the firing-pin will be suddenly projected against the cartridge in the rifle-barrel, the concussion resulting in the discharge thereof. It will, however, be perceived that if the plunger is not retracted and engaged with the dog F' previous to retracting the trigger the only result thereof, so far as the firing mechanism is concerned, will be to rock the dog F', and therefore, although by engaging the dog with the plunger the rifle-barrel may be fired by the firing mechanism of one of the shot-barrels, that

such mechanism is in no wise embarrassed by the auxiliary function which it is made to perform. If desired, however, a third and independent trigger may be provided to actuate the firing mechanism of the rifle-barrel. As now constructed the plunger is retracted by the cocking-arm; but other means may be employed to effect the same result.

As the rifle-barrel and its firing mechanism are virtually independent of the shotgun-barrels and their firing mechanisms, any double-barreled shotgun may be provided with a rifle-barrel and appropriate lock mechanism, after its completion, at a comparatively light expense.

I would have it understood that I do not limit myself to the exact construction and combinations of parts herein shown and described, but that I hold myself at liberty to make such slight changes and alterations as fairly fall within the spirit and scope of my invention.

Having fully described my invention, what I claim as new, and desire to secure by Letters Patent, is—

1. The combination, with a double-barreled breech-loading shotgun having a rifle-barrel attached to the top of and between the shot-barrels, of independent mechanism for firing the rifle-barrel, and devices, substantially as described, connecting said firing mechanism with both of the triggers of the shot-barrels, whereby the retraction of the firing-plunger of the rifle-barrel will enable said plunger to be released by either one of said triggers in firing the rifle.

2. The combination, with a double-barreled breech-loading shotgun having a rifle-barrel attached to the top and between the shot-barrels, of a breech-block having a recess in its upper face, and a lock-frame to inclose the firing mechanism of the rifle-barrel, said frame being provided on its under face with a lug adapted to fit within the said recess in the breech-block.

3. The combination, with a double-barreled breech-loading shotgun having a rifle-barrel attached to the top of and between the shot-barrels, of independent mechanism for firing the rifle-barrel, said mechanism being mounted in a frame removably secured to the top of the breech-block, and devices, substantially as described, connecting said rifle-firing mechanism with both of the triggers of the shot-barrels, whereby the retraction of the rifle-firing plunger will enable it to be released by either one of the triggers, substantially as set forth.

4. The combination, with a double-barreled breech-loading shotgun having a rifle-barrel attached to the top and between the shot-barrels, of independent rifle-firing mechanism mounted on the top of the breech-block, rod T, and the triggers V of the shotgun, substantially as set forth.

In testimony whereof I have signed this specification in the presence of two subscribing witnesses.

WILLIAM T. DAVIS.
